UNITED STATES PATENT OFFICE

147,154

DESIGN FOR A BRACELET OR SIMILAR ARTICLE

John G. Stanley, Norwood, Ohio

Application January 23, 1946, Serial No. 125,878

Term of patent 14 years

(Cl. D45—4)

To all whom it may concern:

Be it known that I, John G. Stanley, a citizen of the United States and a resident of Norwood, in the county of Hamilton and the State of Ohio, have invented a new, original, and ornamental Design for a Bracelet or Similar Article, of which the following is a specification, reference being made to the accompanying drawing, forming a part thereof.

Fig. 1 is a front elevational view of a bracelet showing my new design.

Fig. 2 is an edge view of said bracelet.

Fig. 3 is a rear elevational view of the same.

Fig. 4 is an end view of the bracelet.

I claim:

The ornamental design for a bracelet or similar article, substantially as shown.

JOHN G. STANLEY.
